CLAIM

The ornamental design for a medical threaded screw sleeve for a tibial anchor arrangement for a short surgical graft, as shown and described.

DESCRIPTION

FIG. 1 is a top perspective view of the medical threaded screw sleeve of the present invention;

FIG. 2 is a bottom perspective view thereof;

FIG. 3 is a left side view thereof;

FIG. 4 is a front view thereof;

FIG. 5 is a right side view thereof;

FIG. 6 is a rear view thereof;

FIG. 7 is a top view thereof; and,

FIG. 8 is a bottom view thereof.
